COMPRESSION IGNITION ENGINE

Earl R. Klinge, Detroit, Mich., assignor to Continental Motors Corporation, Detroit and Muskegon, Mich., a corporation of Virginia

Filed Feb. 27, 1958, Ser. No. 718,029

11 Claims. (Cl. 123—30)

My invention relates to compression ignition engines and more particularly to a means for adding ignition accelerator to the fuel delivery system during periods of low load and low speed operation to reduce ignition delay and consequent roughness of the engine.

The present invention is particularly adaptable to compression ignition engines using gasoline or other low ignition quality fuels rather than conventional diesel oil fuels. Such higher octane fuels have comparatively low octane numbers; that is, their ignition quality is not as high as diesel oils for use in compression ignition engines.

High speed diesel engines with compression ratios up to about 20 to 1 may be designed such that ignition delay from the instant of fuel injection is not great enough during normal operation to cause the roughness generally characteristic of compression ignition engines. However, at lower speeds and loads, ignition delay increases due to cooling off of the combustion chamber and the engine loses in efficiency and smooth operation. This can be overcome by increasing the octane number of the fuel through the addition of an ignition accelerator but then the purpose of using gasoline or like fuels is defeated.

An object of the present invention is to improve performance of compression ignition engines operated on fuels of low cetane number by providing a means for adding ignition accelerator to the fuel supply system at predetermined ranges of engine operation.

Another object of the invention is to decrease ignition delay during selected ranges of operation of compression ignition engines by providing means for adding ignition accelerator to the fuel supply system only during these selected ranges of operation.

A further object of the invention is to improve operating characteristics of compression ignition engines using fuels of low cetane number by adding engine lubricating oil to the fuel supply system during selected ranges of engine operation.

Still another object of the present invention is to improve compression ignition engine operation by constructing a fuel injection pump having a valve connecting the delivery side of the pump with a source of ignition accelerator supply and operable to admit ignition accelerator to the fuel being delivered to the engine at selected operating ranges.

A still further object of the invention is to provide an improved means of adding ignition accelerator to the fuel supply system of a compression ignition engine by constructing a valve connected between a source of ignition accelerator supply and the fuel supply system and operable to open in response to a decrease in engine speed and load.

Yet another object of the invention is to utilize engine lubricating oil as an ignition accelerator in compression ignition engines by providing a valve connected between the engine lubricating system and a variable pressure fuel delivery system and operable to open in response to

2

particular changes in fuel pressures at selected engine speeds.

Yet a further object of the invention is to provide a means for adding ignition accelerator to a compression ignition engine by constructing a valve connected between the downstream side of a variable pressure fuel injection pump and a pressurized ignition accelerator supply and operable to open upon a decrease of residual fuel pressure to below the ignition accelerator pressure.

10 For a more complete understanding of the invention, reference may be had to the accompanying drawings illustrating a preferred embodiment of the invention in which like reference characters refer to like parts throughout the several views and in which

15 Fig. 1 is a schematic drawing illustrating a preferred system embodying the invention.

Fig. 2 is a cross-sectional view of a preferred fuel injection pump constructed to utilize a preferred method of adding ignition accelerator to the fuel supply system 20 of a compression ignition engine.

Fig. 3 is a chart illustrating a preferred fuel pressure relationship for utilization in operating the present preferred system.

Fig. 4 is a second chart illustrating a second pressure relationship observable in the preferred system aforesaid, and

Fig. 5 is a cross-sectional view taken substantially on the line 5—5 of Fig. 2 to illustrate a preferred valve construction.

30 The principal characteristic of compression ignition engines using gasoline or like fuels that makes the present invention feasible and desirable is that at low speed engine operating ranges, and at low engine loads, ignition delay becomes too great for efficient and smooth operation. The chief concept of the present invention is to make use of fuel supply system pressures, which vary with engine speed and load, for operating a valve connected between a source of ignition accelerator supply and the fuel supply system.

40 The most available source of ignition accelerator in gasoline fueled compression ignition engine is the engine lubricating system. Obviously means could be provided for adding a continuous small flow of oil to the fuel supply, but this would defeat the purpose of using a

45 gasoline consuming engine and require an excessively large supply of oil. A preferred system embodying the present invention is illustrated in the present drawings, Fig. 1 illustrating a compression ignition engine 10 having a fuel supply source or tank 11 and a lubricating

50 oil supply source or tank 12. A fuel pump 13 pumps fuel under relatively low pressure, which preferably is constant, to a fuel injection pump 14 operable to pump fuel intermittently under high pressure to a fuel injector nozzle 15 of conventional construction and operable to 55 open under a fuel pressure preferably as indicated by the line V.O.P. (valve opening pressure) in the charts. Figs. 3 and 4, the pressure denoted for purposes of discussion being in the neighborhood of about 2500 p.s.i.

A lubricating oil pump 16 is operable to pump oil 60 from the oil tank 12 to the engine 10, preferably under a pressure of about 25 to 50 p.s.i. for purposes of discussion, as indicated by the dotted line O.P. (oil pressure) in the charts.

A valve 17 is preferably connected intermediate the 65 downstream side of the oil pump 16 and the downstream side of the fuel injection pump 14, the valve 17 preferably being a simplified check valve, pressure responsive to open only when fuel delivery pressure drops below oil system pressure.

70 The preferred substantially conventional fuel injection pump 14 is illustrated in more detail in Fig. 2 as comprising a housing 20 provided with a fuel inlet 21,

a fuel spill return outlet 22, a fuel pressure chamber 23, fuel pressure outlets 24, a pumping piston 25, a control chamber 26, a distributing chamber 27, and a pump chamber 28.

The piston 25 is operable to reciprocate up and down, being actuated by a cam 30 mounted on a shaft 31 rotated through a gear 32 connected preferably in any conventional manner to the engine. On the upward stroke of the piston 25, fuel in the pump chamber 28 is put under pressure after the piston closes off a fuel inlet port 33 and a fuel outlet port 34 respectively connected with the inlet 21 and return outlet 22. A spill passage 35 extends through the piston 25 from the pump chamber 28 to the control chamber 26, being opened when the piston 25 has moved a distance sufficient to permit a spill port 36 to clear a control valve sleeve 37 disposed in the control chamber 26, thus relieving pressure in the pump chamber 28, the control chamber 26 being connected through passages 38 and 39 respectively with the inlet 21 and return outlet 22.

The length of piston stroke prior to relief of pressure in the pump chamber 28 determines the volume of fuel delivered and is controlled by variations in axial position of the control valve sleeve 37. Any suitable control means such as a crank element 45 may be used to vary the axial position of the sleeve 37. For purposes of the present discussion, the actual means for controlling axial adjustment of the sleeve is immaterial, and are omitted here.

The fuel under pressure in the pump chamber 28 operates to open a conventional retraction type discharge check valve 46 against the pressure of a return spring 47, the fuel passing through a passage 48 in the retraction valve to an annular groove 49 and then passing into the fuel pressure chamber 23 when the upper piston 50 of the valve 46 clears the upper end of a valve cylinder 51. The fuel under pressure then passes through a port 52 into a delivery chamber 53. The fuel then flows out a passage 55 to the annular distributing chamber 27 adjacent the pump piston 25.

In pumps of the present type, called single piston pumps as differentiated from multiple piston pumps, the fuel is distributed to a plurality of fuel pressure outlets 24, only one of which is here illustrated in detail. The piston 25 is made to rotate by any desired means (not shown), and is provided with a groove or flute 60 which is openly connected with the annular distributing chamber and alternately openly connected with ports 61 (only one shown herein), each of which communicates by a passage 62 with respective fuel outlets 24, which are connected in turn to the fuel injector nozzles 15, only one of which is shown in Fig. 1.

The nozzle 15 is preferably of the conventional type having a fixed nozzle orifice area. Thus, with a constant volume of fuel being pumped intermittently into the delivery system during engine operation, intermittent fuel pressure in the line to the nozzle 15 will rise to a higher peak than the nozzle valve opening pressure, as indicated by the upper ascending line A—A in Fig. 3, so that on each stroke, the nozzle operates to inject fuel into the engine combustion chamber (not shown). Since the time during which this constant volume of fuel is pumped into the line decreases as the engine r.p.m. increases, the peak line pressure will rise to correspondingly higher values above valve opening pressure as engine r.p.m. increases, due to the fixed nozzle orifice area of the nozzle 15.

As soon as fuel pressure is relieved from the pump chamber 28, representing the effective end of the piston stroke, the return spring 47 moves the retraction valve 46 downward. The retraction valve 46 is so constructed that the piston 50 engages the upper end of the valve cylinder 51, closing communication between the pump chamber 28 and the pressure chamber 23, prior to full seating of the valve 46. Thus the volume of the delivery

system between the retraction valve 46 and the injector nozzle 15 is increased by a predetermined increment, causing line pressure in that portion of the system to decrease immediately, proportionately with the increase in volume. This is a conventional manner of preventing after-dripping from the injector nozzle, the degree of retraction valve motion after fuel cut-off being selected to always reduce line pressure below nozzle valve opening pressure, so that the injector nozzle will close immediately after injection, and the residual pressure remaining in the line after such line-unloading is indicated by the lower solid ascending line B—B in Fig. 3. This residual pressure will be in substantially direct ascending relationship with increasing fuel delivery pressure, due to the substantially uniform line-pressure drop.

The position of the sleeve 37 in the control chamber 26 is regulated relative to engine loads. Thus, at lower loads, the sleeve 37 is positioned lower in the control chamber 26 to relieve pressure after a relatively short piston stroke, so that the delivered fuel quantity per stroke is smaller, and since this volume is pumped through a fixed area nozzle orifice, the maximum or peak line pressure is relatively low. At higher engine loads, the sleeve 37 is positioned higher in the control chamber 26 to relieve pressure after a relatively longer piston stroke, so that the delivered fuel quantity per stroke is larger, and again being pumped through the same fixed area nozzle orifice, the maximum or peak line pressure is relatively higher. If the volume of fuel is pumped into the line over a long enough time period, line pressure would reach an equilibrium dependent upon the size of the nozzle orifice and the volume of fuel delivered, but since pressure is relieved before equilibrium pressure is reached, the peak line pressure at different volumes in the present system will be characterized by the upper ascending curve A'—A' of Fig. 4. Pressure drop due to the operation of the fixed retraction valve 46 as previously described will produce a residual pressure curve such as B'—B' in Fig. 4.

An oil inlet 63 is provided in the pump housing 20 and is normally closed by the check valve 17 by the pressure of fuel in the delivery chamber 53. However, as is noted in the charts of Figs. 3 and 4, residual fuel pressure drops below the pressure of oil in the fuel system at certain lower engine speeds (Fig. 3), and lower loads (Fig. 4) such that the valve 17 opens and the oil will be injected into the fuel delivery system, raising the cetane number of the fuel and acting as an ignition accelerator in the engine combustion chamber according to well recognized compression ignition engine principles.

Obviously, oil pressure and residual pressure may be so controlled to provide for opening of the check valve 17 only at those low speeds and fuel loads at which ignition delay would cause rough and inefficient engine operation.

In the present case, selected for purposes of discussion, Fig. 3 illustrates an engine having fuel peak line delivery pressures above about 25000 p.s.i., variable as engine speed varies over a range of about 1000 to 3000 r.p.m., so that line pressure drop provides residual pressure of under about 2500 p.s.i., varying downward from under 2500 p.s.i. to below 25 to 50 p.s.i.

Thus, in net effect, ignition accelerator, in the present case being drawn from the engine lubricating system, is added to the fuel at selected ranges of low speed and low load engine operation.

Although I have described only one preferred embodiment of the invention, it will be apparent that various changes and modifications therein may be made without departing from the spirit of the invention or the scope of the appended claims.

I claim:

1. In a fuel supply system for a compression ignition engine, means delivering said engine fuel under pressure variable relative to engine speed and load, a source of

ignition accelerator supply, and a pressure responsive valve connected intermediate said delivery means and said ignition accelerator supply and actuated upon a decrease of fuel pressure to open and admit ignition accelerator into said fuel, said source of ignition accelerator supply comprising a lubricating oil system connected with said engine.

2. In a fuel supply system for a compression ignition engine, means delivering to said engine fuel under pressure variable relative to engine speed and load, a source of ignition accelerator supply, and a pressure responsive valve connected intermediate said delivery means and said ignition accelerator supply and actuated upon a decrease of fuel pressure to open and admit ignition accelerator into said fuel, said delivery means comprising a fuel injection pump operable to intermittently pump fuel under pressure to said engine and having means retaining downstream of said pump between pressure strokes a residual fuel pressure variable relative to engine speed and load, said valve being connected with said delivery means downstream of said pump and operable to open only in response to decrease of residual fuel pressure to a predetermined value.

3. In a fuel supply system for a compression ignition engine, means delivering to said engine fuel under pressure variable relative to engine speed and load, a source of ignition accelerator supply, and a pressure responsive valve connected intermediate said delivery means and said ignition accelerator supply and actuated upon a decrease of fuel pressure to open and admit ignition accelerator into said fuel, said source of ignition accelerator supply comprising a lubricating oil system connected with said engine, means obtaining oil pressure in said lubricating oil system, said valve being operable only in response to a differential between fuel pressure and oil pressure.

4. In a fuel supply system for a compression ignition engine, means delivering to said engine fuel under pressure variable relative to engine speed and load, a source of ignition accelerator supply, and a pressure responsive valve connected intermediate said delivery means and said ignition accelerator supply and actuated upon a decrease of fuel pressure to open and admit ignition accelerator into said fuel, said source of ignition accelerator supply comprising a lubricating oil system connected with said engine and having an oil pump for pressurizing said oil, said delivery means comprising a fuel injection pump operable to intermittently pump fuel under pressure to said engine and having means retaining downstream of said pump between pressure strokes a residual fuel pressure variable relative to engine speed and load, said valve being connected with said delivery means downstream of said pump and operable only in response to a differential between said residual fuel pressure and lubricating oil pressure.

5. In a fuel supply system for a compression ignition engine, means delivering to said engine fuel under pressure variable relative to engine speed and load, a source of ignition accelerator supply, and a pressure responsive valve connected intermediate said delivery means and said ignition accelerator supply and actuated upon a decrease of fuel pressure to open and admit ignition accelerator into said fuel, said source of ignition accelerator supply comprising a lubricating oil system connected with said engine and having an oil pump for pressurizing said oil, said delivery means comprising a fuel injection pump operable to intermittently pump fuel under pressure to said engine and having means retaining downstream of said pump between pressure strokes a residual fuel pressure variable relative to engine speed and load, said valve being connected with said delivery means downstream of said pump and operable only in response to a differential between said residual fuel pressure and lubricating oil pressure, said oil pressure being such as to be higher than residual fuel pressure only when said engine is

operating at relatively low load and low speed, whereby admission of lubricating oil into said delivery system acts to decrease fuel ignition delay.

6. In a fuel supply system for a compression ignition engine, a fuel injector nozzle having a valve operable to open at a predetermined fuel pressure, a fuel ignition pump connected with said nozzle and operable to deliver fuel thereto intermittently at a pressure above said nozzle valve opening pressure and variable relative to engine speed and load, said pump having means increasing the volume of said supply system downstream of said pump immediately following each pump pressure stroke to decrease fuel pressure downstream of said pump by a uniform increment sufficient to obtain a residual pressure below said nozzle valve opening pressure and variable relative to engine speed and load, a source of ignition accelerator supply and means maintaining same at a substantially fixed predetermined pressure below said nozzle valve opening pressure, a pressure responsive valve connected intermediate said ignition accelerator supply and said fuel supply system downstream of said pump, said pressure responsive valve being operable to open only when said residual fuel pressure falls below said ignition accelerator supply pressure to admit ignition accelerator into said fuel supply system.

7. In a fuel supply system for a compression ignition engine, a fuel injector nozzle having a valve operable to open at a predetermined fuel pressure, a fuel injection pump connected with said nozzle and operable to deliver fuel thereto intermittently at a pressure above said nozzle valve opening pressure and variable relative to engine speed and load, said pump having means increasing the volume of said supply system downstream of said pump immediately following each pump pressure stroke to decrease fuel pressure downstream of said pump by a uniform increment sufficient to obtain a residual pressure below said nozzle valve opening pressure and variable relative to engine speed and load, a lubricating oil system connected with said engine and means maintaining same at a substantially fixed predetermined pressure below said nozzle valve opening pressure, a pressure responsive valve connected intermediate said oil system and said fuel supply system downstream of said pump, said pressure responsive valve being operable to open only when said residual fuel pressure falls below said oil pressure to admit lubricating oil into said fuel supply system for accelerating engine ignition.

8. In a fuel supply system for a compression ignition engine having a lubricating oil system, a fuel injection pump for pumping fuel to said engine and comprising a casing having a fuel inlet, a fuel outlet, a fuel pressure chamber openly connected with said fuel outlet, means in said casing intermittently pumping fuel under pressure into said pressure chamber, a lubricating oil inlet openly connected with said engine lubricating oil system, a pressure responsive valve connected intermediate said oil inlet and said fuel pressure chamber and actuated upon a decrease of fuel pressure to a predetermined value to open and admit lubricating oil into said fuel pressure chamber for accelerating engine ignition.

9. In a fuel supply system for a compression ignition engine having a lubricating oil system, a fuel injection pump for pumping fuel to said engine and comprising a casing having a fuel inlet, a fuel outlet, a fuel pressure chamber openly connected with said fuel outlet, means in said casing intermittently pumping fuel under pressure into said pressure chamber, a lubricating oil inlet openly connected with said engine lubricating oil system, said lubricating oil system having means maintaining a substantially fixed predetermined oil pressure, said injection pump having a check valve connected intermediate said oil inlet and said fuel pressure chamber and operable to open only when fuel pressure in said chamber drops below said oil pressure to admit lubricating oil into said fuel pressure chamber to accelerate engine ignition.

10. A fuel supply system for a compression ignition engine, comprising a fuel injection pump for delivering fuel under pressure to said engine, means retaining downstream of said pump a residual fuel pressure variable relative to engine speed and load, a source of ignition accelerator supply, and pressure responsive means operable to selectively introduce ignition accelerator into the fuel delivered to said engine in response to a predetermined variation of the aforesaid residual fuel pressure.

11. A fuel supply system for a compression ignition engine comprising a fuel injection pump for delivering fuel under pressure to said engine, means retaining downstream of said pump a residual fuel pressure variable

10

relative to engine speed and load, an ignition accelerator supply system having means obtaining pressure therein, and pressure responsive means operable in response to a predetermined variation of pressure differential between residual fuel pressure and ignition accelerator pressure to introduce ignition accelerator into the fuel delivered to said engine.
